UNITED STATES PATENT OFFICE.

JAMES BURKE, OF CLEVELAND, OHIO.

TRACK-CONSTRUCTION MACHINE.

1,015,475.

Specification of Letters Patent. Patented Jan. 23, 1912.

Application filed April 29, 1911. Serial No. 624,239.

To all whom it may concern:

Be it known that I, JAMES BURKE, a citizen of the United States of America, residing at Cleveland, in the county of Cuyahoga and State of Ohio, have invented certain new and useful Improvements in Track-Construction Machines; and I hereby declare the following to be a full, clear, and exact description of the invention, such as will enable others skilled in the art to which it pertains to make and use the same.

This invention relates to new and useful improvements in machines for removing old ties and placing new ties on railways without disturbing the rails.

The object of this invention is to provide a machine which will be strong and durable, which can be economically and rapidly operated and which will remove one tie and place a new one with the least amount of manual labor on the part of the gang operating the machine.

A further object of my invention is to provide in a machine of this character means for readily and quickly removing the machine from the track on which it may be standing when in operation so as to permit the passage of the regular trains on the road without causing any delay to the same.

My invention, therefore, consists primarily in providing in a machine of this character means for engaging a tie and moving it transversely of and beneath the rails of a track so as to either remove a tie from beneath the rails or place a tie in the groove left by the removal of a tie from beneath the rails.

My invention further consists in providing an independent or auxiliary truck at each end of the machine and means for normally supporting the truck so that the wheels thereof will be held above the track on which the main wheels of the machine rest and means for lowering the said trucks so as to bring the wheels thereon into contact with an auxiliary track laid across the main track and means for causing an upward movement of the whole machine after the wheels of the auxiliary truck have been brought into contact with the auxiliary track so as to lift the main wheels above the said auxiliary track.

My invention also consists in the features of construction and combination of parts described in the specification, pointed out

in the claims and illustrated in the accompanying drawings.

Referring to the drawings Figure 1 is a top plan of a machine embodying my invention. Fig. 2 is a side elevation of the same. Fig. 3 is a section on line 3—3 Fig. 2. Fig. 4 is an end elevation of a machine showing the auxiliary trucks resting on the auxiliary tracks and the machine shifted to one side of the main track. Fig. 5 is a section on line 5—5, Fig. 2. Fig. 6 is a section on line 6—6; Fig. 5. Fig. 7 is a section on line 7—7, Fig. 5. Fig. 8 is a section on line 8—8, Fig. 6. Fig. 9 is an end elevation of the machine showing the tie placing member extending out and in engagement with the tie so as to force the same into position.

Again referring to the drawings 1 represents the platform of an ordinary flat car which is provided with the usual trucks 2 including axles 3 and wheels 4. On the platform 1 is mounted a boiler 6 and an engine 7 which has the usual steam connection with the boiler 6. The engine 7 is of the usual vertical reversible type and is provided with a crank shaft 9 having at one end a fly wheel 10 and at its opposite end a coupling device 11 by which the crank shaft is connected with a short shaft 12 which is mounted in a support 13 arranged on the platform 1. On the short shaft 12 is rigidly secured a gear wheel 14.

The arrangement for connecting the engine with the driving means of the machine is as follows:—At one side of and parallel with the shaft 12 is journaled a short shaft 15 in supports 16, which are mounted on the platform 1. On the shaft 15 is loosely mounted a gear wheel 17 arranged to mesh with the gear wheel 14 on the shaft 12. The gear wheel 17 has formed integral therewith a clutch member 18, and on the said shaft 15 is slidably mounted a clutch member 19 so as to rotate with said shaft 15. A clutch lever 20 is mounted on the platform 1 in the usual manner, and is operatively connected with the slideable clutch member 19 so that by shifting the said lever 20 the said clutch member can be brought into engagement with the clutch member 18 on the gear wheel 17, thereby locking said gear 17 to the shaft 15. A shaft 23 is hung from the under side of the platform 1 by hangers 24 and on the upper end of said shaft is rigidly secured

a beveled gear 25 which meshes with the gear wheel 17, and on the lower end of said shaft is rigidly secured a beveled gear 26 which meshes with a beveled gear 27 rigidly secured on the axle 3. It will therefore be seen that when the engine is started and the lever 20 shifted so as to cause an engagement of the clutch members the engine through the operative connection just described will drive the wheels 4 so as to propel the car as desired in a forward direction, and of course by simply reversing the engine the car can be caused to travel in the opposite direction.

15 The tie placing and extracting mechanism is mounted and arranged as follows: To the under side of the platform 1 is rigidly secured a double row of brackets 32 and between said brackets are supported two channel bars 33 which are placed with their flanges touching so that they form a rectangular guideway which extends from side to side transversely of the car. On each of the inner faces of this guideway are mounted a 20 series of rollers 37. In the space between the said rollers is a beam 38 which is preferably formed of channel bars similarly to the guideway and the channel bars are secured together by plates 39. It will therefore be seen that the said beam will be supported at all times by the rollers 37, and the said beam will be free to move longitudinally of the said guideway so that it can be caused to project beyond the guideway at 25 either side of the machine as desired. The means for actuating the said beam is arranged as follows: On one side of the beam 38, and extending longitudinally thereof is secured a rack bar 40 by means of bolts 41. 30 On the platform 1, in suitable supports 48, is journaled a shaft 49 which extends parallel with the shaft 12 which is connected to the engine shaft. At one end of this shaft is loosely mounted a gear 50 which carries the 35 clutch member 51 formed integral therewith and on the shaft 49 is slidably mounted a clutch member 52 so as to turn with said shaft 49. A clutch lever 53 is operatively connected with the clutch member 52 by 40 means of which the said clutch member 52 can be shifted into or out of engagement with the clutch member 51 on the gear wheel 50. On the opposite end of said shaft 49 is rigidly secured a bevel 45 gear 54. A shaft 56 is mounted on the platform 1 in supports 57, the said shaft 56 being arranged at a right angle to the shaft 49. On the said shaft 56 is slidably mounted a sleeve 58 so as to turn with the said shaft, 50 and on the ends of said sleeve are rigidly secured bevel gears 59 which can be caused to engage with the bevel gear 54 on the shaft 49 by shifting the said sleeve in one direction or the other. It will of course be understood that when the bevel gear 59 on one end

of the sleeve is in mesh with the bevel gear 54 on the shaft 49 the shaft 56 will be driven in one direction and when the bevel gear on the other end of the sleeve 58 is in engagement with the bevel gear 54 said shaft 56 will be driven in the opposite direction. At each end of the shaft 56 is formed a worm 61. At each side of the platform 1, in proximity to the ends of the shaft 56, are vertically arranged shafts 62, the said shafts being supported in bearings 64 secured on the side of one of the channel bars 33. On the upper ends of the said shafts 62 are rigidly secured worm gears 63 arranged to mesh with the worms on the ends of the shaft 56. 70 On each of the vertically arranged shafts 62 below the platform are rigidly secured gears 66 in line with the rack 40 on the beam 38, the channel bar 33 being provided with a slot 67 through which the said gear wheels 66 extend so that they can engage with the said rack bar 40. Now when the engine is operated and the slideable clutch 52 is brought into engagement with the clutch member 51 the shaft 49 will be driven 75 through its operative connection with the engine shaft and the said shaft 49 in turn will drive the shaft 56 which in turn will drive the vertical shaft 62 which will rotate the gear wheels 66 in engagement with the rack bar 40 and the beam 38 will therefore be caused to move longitudinally of its supporting guideway and project beyond one end thereof according to the direction in which the shaft 56 is driven. In order to draw the beam 38 back into the guideway it is only necessary to shift the sleeve 58 so as to bring the gear 59 thereon which was not in engagement with the gear 54 into engagement with the gear 54. 80

105 In each end of the beam 38, which we may designate as the tie handling beam, is formed a vertical guideway 69 in which is mounted a bar 70 having rack teeth 70' formed along one side thereof. At the lower end of said bar 70 is formed a hook 71. A small horizontally arranged shaft 72 extends from side to side of the tie handling beam 38 in proximity to said bar 70 and thereon is rigidly secured a gear wheel 73 which is arranged to mesh with the teeth 70' on the bar 70 and on said shaft 72 is also secured a worm gear 74. A worm 76 is supported in suitable bearings 77 so as to engage with the worm gear 74, and at the end of said worm is provided a crank handle 78. It will therefore be seen that by turning the crank handle 78 in either direction the worm 74 will be revolved causing a rotation of the shaft 72 which revolves the gear wheel 73 which meshes with the teeth 70' on the bar 70 so that said bar will be raised or lowered according to the direction in which the crank handle is turned. 110

115 Now in order to allow the machine to be 120

- readily removed from the main tracks on which it is standing while laying the ties *J* provide the following arrangement: At each end of the platform *I* is mounted a pair of cylinders *S*, the said cylinders being provided with the usual pistons *S* from which piston rods *S* extend downwardly through the said platform *I*, and on the lower ends of said piston rods *S* is arranged a truck *S* including axles *S* and flanged wheels *S*. The pistons can be operated by any suitable fluid or gas and in the drawings is shown a compressed air tank *S* which is designed to supply air for this purpose.
- Now when it is desired to remove the machine from the track, auxiliary rails *S* are laid over and transversely of the main rails in the proper position to be engaged by the wheels *S* when the trucks *S* are lowered.
- Air is then admitted to the cylinders *S* which forces down the pistons *S* and brings the trucks *S* onto the auxiliary rails *S* and when the wheels come in contact with said rails and more air is admitted to the cylinders the whole machine is raised from the main track a sufficient distance to allow the main wheels to clear the said track and the machine will then be supported entirely on the auxiliary trucks and the machine can then be moved along the auxiliary rails transversely of the main track and when the machine has been moved to the side of the main track the auxiliary rails are taken off of the main track. In order to do this conveniently the auxiliary rails are preferably jointed as shown at *S*, which permits the said auxiliary rails to be swung up to an approximately vertical position as shown in dotted lines in Fig. 4. The main track will then be entirely clear for the passage of a regular train and after the train has passed the auxiliary rails are swung down and the machine moved back to its operative position on the main track.
- The operation of the machine itself is as follows: The machine is placed on the track and the lever controlling the connection between the engine and the traction wheels is operated and the machine will then travel on the main track to whatever point repairs or construction work is necessary. When the place is reached where an old tie is to be replaced with a new tie the engine is disconnected from the traction wheels and the lever which controls the connection between the engine and the mechanism for moving the tie handling beam is operated. When the mechanism starts to operate the tie handling beam will be run out at whichever side of the machine it is most convenient for operating from and the hook on the outer end of said beam will be caused to engage the end of the new tie, as shown in Fig. 8, where the tie, indicated at *a*, is shown in dotted lines. The other end of the tie is placed against the old tie which is to be removed. The mechanism for moving the tie handling beam is then reversed and the beam is drawn back into its guideway and the hook *S* in engagement with the new tie shoves the tie ahead of it underneath the rails shoving out the old tie. In locations where it is not possible, owing to lack of space, to shove the old tie out at the opposite side from that on which the new tie is inserted the old tie can be coupled in any suitable way to the tie handling beam, as by means of a chain, and drawn out from under the rails as the tie handling beams moves out of the guideway so that it will be drawn out from under the rails at the same side at which the new tie is inserted.
- What I claim is,—
1. In a machine of the character described, the combination of a platform, main trucks secured to said platform and adapted to have traction on a main track of a railroad, cylinders mounted on said platform and provided with pistons and piston rods, auxiliary trucks operatively connected with said piston rods means for supplying an actuating medium to said cylinders so as to force down the piston rods and bring the said auxiliary trucks in contact with an auxiliary track arranged above the main track and lift said platform together with the main trucks secured thereto away from the main track.
  2. A machine of the character described comprising a platform, an engine mounted on said platform, a tie handling beam supported from said platform and adapted to move transversely of said platform, means for moving said beam, means for connecting the means for moving the beam with the engine and means arranged on said tie handling beam for engaging the tie.
  3. A machine of the character described comprising a platform, trucks secured to said platform, an engine mounted on said platform, driving mechanism for operatively connecting the wheels of the truck at one end of the platform with said engine, a tie handling beam supported from said platform and adapted to move transversely of said platform, means for moving said tie handling beam so as to cause said tie handling beam to extend beyond said platform at either side thereof and means for connecting said engine with said tie handling beam.
  4. A machine of the character described comprising a platform, trucks secured to said platform, an engine mounted on said platform, a guideway supported from said platform, rollers mounted in said guideway, a tie handling beam arranged in said guideway on said rollers, means for moving said tie handling beam in and out of said guideway, means for connecting said engine with said means for moving said tie handling beam.

- beam and means arranged on said tie handling beam for engaging a tie.
5. A machine of the character described comprising a platform, trucks secured to said platform, an engine mounted on said platform, a guideway supported from said platform, rollers mounted in said guideway, a tie handling beam arranged in said guideway on said rollers, means for moving said tie handling beam in and out of said guideway, means for connecting said engine with said means for moving said tie handling beam and a hook adjustably supported at the end of said tie handling beam and adapted to engage with a tie.
10. 6. A machine of the character described comprising a platform, trucks secured to said platform, an engine mounted on said platform, a guideway supported from said platform, a tie handling beam arranged in said guideway, a rack bar arranged on said tie handling beam, a vertically arranged shaft mounted on said platform and provided at its lower end with a gear wheel adapted to mesh with the rack on said beam and means for operatively connecting said shaft with said engine so as to drive said shaft in either direction.
15. 7. A machine of the character described comprising a platform, trucks secured to said platform, an engine mounted on said platform, a guideway supported from said platform, a tie handling beam arranged in said guideway, a rack bar arranged on said tie handling beam, a vertically arranged shaft mounted on said platform, a gear wheel secured on the lower end of said shaft and adapted to mesh with the rack on said beam, a gear wheel secured at the upper end of said shaft, a horizontal shaft mounted on said platform and having a worm at one end
- thereof adapted to mesh with the gear wheel at the upper end of the vertical shaft and means for operatively connecting said horizontal shaft with the said engine so that said engine will rotate said shaft.
- 45
8. A machine of the character described comprising a platform, trucks secured to said platform, an engine mounted on said platform, a guideway supported from said platform, a tie handling beam arranged in said guideway, a rack bar arranged on said tie handling beam, a vertical shaft arranged at each side of said platform, gear wheels secured on the lower ends of said vertical shaft and adapted to mesh with the rack bar on the tie handling beam, a shaft mounted on the said platform and extending transversely thereof and provided at each end with worms, worm gears secured on the upper end of said vertical shaft and adapted to mesh with the worms on the transversely extending shaft, a sleeve arranged on said transversely extending shaft, and provided at each end with a bevel gear, means for shifting said sleeve, a longitudinally extending shaft mounted on said platform, a bevel gear secured on the end of said longitudinally extending shaft and adapted to mesh with one or the other of said bevel gears on said sleeve according to the position of said sleeve and means for operatively connecting said longitudinally extending shaft with the engine, for the purpose set forth.
